United States Patent Office

Des. 196,425
Patented Oct. 1, 1963

196,425

RESTAURANT BUILDING

Norman J. Kasser, 1115 Devon Road, Rydal, Pa.

Filed Feb. 13, 1962, Ser. No. 68,803

Term of patent 14 years

(Cl. D13—1)

Des. 196,425

PAGE 2

Des. 196,425

The dominant features of my design reside in the portions shown in full lines.

I claim:

The ornamental design for a restaurant building, as shown and described.
